UNITED STATES PATENT OFFICE.

JOHN ALFRED HUGHES DREW, OF FITZROY, AND HENRY JAMES DREW, OF NORTH FITZROY, MELBOURNE, VICTORIA, AUSTRALIA.

DETACHABLE HEEL FOR FOOTWEAR.

1,160,152.

Specification of Letters Patent. Patented Nov. 16, 1915.

Application filed August 23, 1915. Serial No. 46,947.

To all whom it may concern:

Be it known that we, JOHN ALFRED HUGHES DREW, a subject of the King of Great Britain and Ireland, and a resident 5 of the city of Fitzroy, a suburb of the city of Melbourne, in the county of Bourke, State of Victoria, Commonwealth of Australia, (whose post-office address is 137 Gertrude street, in the said city of Fitzroy,) and 10 HENRY JAMES DREW, a subject of the King of Great Britain and Ireland, and a resident of the postal district of North Fitzroy, a suburb of the city of Fitzroy, a suburb of the city of Melbourne, in the county of 15 Bourke, State of Victoria, Commonwealth of Australia, (whose post-office address is 4 Reid street, in the said postal district of North Fitzroy,) have invented certain new and useful Improvements in or Relating to 20 Detachable Heels for Footwear, of which the following is a specification.

This invention relates to detachable heels for footwear of the kind wherein a heel may be readily removed and renewed when worn. 25 Hitherto a number of heels of this character have been suggested, many of which, however, have been liable to loss causing inconvenience to the wearer. In addition, they have not always been capable of being easily 30 applied or removed in a minimum of time as when screws have been employed to retain the heels it has generally been necessary to entirely remove the screws, to replace worn heels for example. Some heels also have 35 been of a somewhat complicated construction and costly to manufacture. Further, it is generally obvious that detachable heels are attachments to the fixed heels of the footwear.

40 The object of this invention is to provide a heel which may be applied or removed and interchanged in a minimum of time, is cheap, simple, light and not liable to sudden loss. It is also only necessary to 45 slightly slacken and not to remove retention screws when it is desired to remove and renew a heel. In addition, it is not readily apparent to the eye that the invention is an attachment to the heel of the boot or shoe.

50 Referring to the drawings which form a part of this specification:—Figure 1 is a side elevation of the fixed heel of a boot or shoe showing retention screws carried thereby. Fig. 2 is a reverse perspective view of 55 a holding plate used with a detachable

leather heel. Fig. 3 is a sectional view of the holding plate seen in Fig. 2. Fig. 4 is a reverse plan of a holding plate used with a rubber heel. Fig. 5 is a longitudinal section on line A—A, Fig. 4. Fig. 6 is a cross section on line B—B, Fig. 4. Fig. 7 is a perspective view of a leather heel according to this invention. The holding plate is removed. Fig. 8 is a perspective view of a complete rubber heel according to the invention. Fig. 9 is a front end view of the fixed heel of a boot or shoe carrying a detachable leather heel according to the invention, the holding plate and leather lifts or laminations being assembled. Fig. 10 is 70 a sectional view of the fixed heel of a boot or shoe carrying a rubber heel according to the invention, the embedded holding plate being clearly seen.

The invention is applied to the fixed heel 75 2 of a boot or shoe. Secured to the bottom of the heel is a front and a back retention screw disposed in a longitudinal line or one behind the other. More than two screws may be employed. Each screw has a shank 80 3 projecting beyond the lower face of the heel. Integral with the shank is a coned bearing surface 4 disposed between the said shank and the head 5 of the screw, as is usual in most screws.

The invention includes a holding plate 6 of the same conformation but preferably slightly smaller in area than the fixed heel 2. The plate is provided with a front edge 7, two side edges 8, and a rounded back edge 9. In cross section the holding plate may be concave both longitudinally and laterally. Formed in the plate 6 is a central longitudinal elongated depression having a wall 10 and a bottom 11. This depression passes from the front edge of the said plate toward the back edge. Its length will depend upon circumstances, as also will its width and depth. Formed in the longitudinally depressed portion of the plate is a 100 front and a back screw head entrance hole, indicated at 12. The distance between the holes corresponds with the distance between the retention screws carried by the fixed heel 2 of the footwear. Passing backwardly 105 from each entrance hole 12 is a reduced passageway, indicated at 13, having spring sides inclined toward each other, as at 14, and upwardly away from the entrance hole, as at 15. With each reduced passageway 110

13 communicates a screw head retention hole indicated at 16, the edge of which is upturned and inwardly inclined forming a circumferential lip 17. The inclined lip 17 forms a bed for the coned bearing surface 4 of the corresponding screw head 5. Formed by the inclined lip 17 of each retention hole 16 is a screw head pocket.

Formed between the front edge 7 of the holding plate 6 and the front screw head entrance hole 12 is a front bridge 18. This extends across the central longitudinal depression of the said holding plate. Formed between the front screw head retention hole 16 and the back screw head entrance hole 12 is a back bridge 19 extending across the central longitudinal depression of the holding plate. Out-pressed from the holding plate 6 is a series of retention tongues 19^a. Each tongue is pointed.

Secured by the tongues 19^a of the holding plate 6 is a heel formed of leather or the like. This heel consists of an upper lift or lamination and a lower lift or lamination. The upper lift 21 is made U-shaped or in the form of a horse-shoe. The lower lift or lamination 24 also comprises a horse shoe or U-shaped conformation. In practice the tongues 19^a are preferably first driven into and through the upper lift. The points of the tongues protrude and are bent over. The lower lift is then secured to the upper lift by brads, nails or the like. Additional lifts may be used if desired.

Instead of employing leather or like material for use with the holding plate 6, rubber or other resilient material 29 may be employed. The holding plate is provided with a series of out-pressed tongues 30 some of which may be opposed. Formed in the holding plate is a plurality of idle holes, indicated at 30^a. The plate is then embedded in the said material 29 which is provided with an upper surface 31 bearing against the fixed heel 2 of the footwear and a lower wearing surface 32. Formed in the lower surface 32 of the resilient heel is an elongated depression or cavity indicated at 33, formed in which are screw slotways, indicated at 34, corresponding with the entrance holes, passageways and retention holes of the holding plate. Across each slotway 34, before the resilient heel is applied to the fixed heel 2, is a jointing web 35.

To apply the invention to the fixed heel of a boot or shoe two retention screws are first driven into the said fixed heel 2, one behind the other, the distance apart corresponding with the distance between the entrance holes 12 in the detachable heel. The heads 5 of the screws are now passed through the front and back entrance holes 12 of the holding plate 6 of the detachable heel. The heel is then pushed forwardly toward the toe of the footwear, the sides of

the reduced passageway 13 passing from each entrance hole 12 bearing beneath the screw head 5. As the heel is pressed into position the said sides of each passageway 13 spring or give permitting the heel to move until the screw heads 5 are accommodated in the pockets formed by the screw head retention holes 16. The heel cannot now be moved backwardly or from position without using pressure and cannot fall from the boot because of the inclined lips 17 of the retention holes 16. The screws are screwed home, the coned bearing surfaces 4 of the retention screws bearing upon the screw head beds formed by the lips 17. In the case of a resilient heel the webs 35 when broken serve to form a joint between the fixed and detachable heels, preventing the entrance of foreign matter around the screws. To remove the heel it is only necessary to slightly slacken the screws when the said heel may be moved backwardly and sprung from position. The operation is the same either with a leather or like heel or with a resilient heel.

Having now described our invention what we claim as new and desire to secure by Letters Patent is:—

1. The combination with a fixed heel carrying a plurality of retention screws, of a detachable heel having a holding plate provided with a plurality of elongated screw-holes, said screw-holes having spring sides adapted to be sprung apart to admit the shank of each screw at an end of each screw-hole and confine the screws for fastening the holding plate to the heel.

2. In a detachable heel for footwear, a holding plate having formed therein a plurality of screw-head entrance and retention holes and passageways formed between the entrance and retention holes, the sides of the passageways being flexible, said flexible sides of the passageways being adapted to be sprung apart to admit the screws into the retention holes and confine the holding plate to the heel.

3. In a detachable heel for footwear, a holding plate having formed therein a plurality of screw head entrance holes passing from each of which is a reduced passageway having spring sides inclined toward each other and upwardly away from the entrance hole, said plate having a plurality of screw head retention holes formed therein each retention hole being provided with an inclined circumferential lip and communicating with the passageway of an entrance hole.

4. A detachable heel for footwear, consisting of a holding plate having formed therein a plurality of screw-head entrance and retention holes and passageways formed between the entrance and retention holes, a heel of resilient material in which the holding plate is embedded, said heel having a

depression formed in its lower surface and having screw slot-ways formed in the depression and corresponding in position with the entrance and retention holes of the embedded holding plate, and means formed over the slot-ways for forming a closure to prevent the entrance of foreign matter around the screws.

5. A detachable heel for footwear consisting of a holding plate having formed therein a plurality of screw head entrance holes passing from each of which is a passageway having spring sides, said plate having a plurality of screw head retention holes formed therein each retention hole communicating with the passageway of an entrance hole, and a heel of resilient material in which the holding plate is embedded, said heel having a depression formed in its lower surface and having screw slotways formed in the depression and corresponding in position with the entrance and retention holes of the embedded holding plate.

6. The combination with a fixed heel carrying depending screws each having a coned

bearing surface, of a holding plate provided with a series of out-pressed tongues and idle holes, said plate having a plurality of screw head entrance holes passing from each of which is a reduced passageway having 30 spring sides inclined toward each other and upwardly away from the entrance holes, said plate having a plurality of screw head retention holes formed therein each retention hole being provided with an inclined 35 circumferential lip and communicating with the passageway of an entrance hole, and a heel of resilient material in which the holding plate is embedded, said heel having formed therein screw slotways correspond- 40 ing in position with the entrance and retention holes of the holding plate.

In testimony whereof we have hereunto affixed our signatures in the presence of two subscribing witness.

JOHN ALFRED HUGHES DREW
HENRY JAMES DREW.
